United States Patent Office

Des. 212,421

Patented Oct. 15, 1968

212,421

TELEVISION TELEPHONE

Paul Hans Thiess, 16 Luxemburgerstrasse,
8 Munich 23, Germany

Filed Sept. 12, 1967, Ser. No. 8,571

Claims priority, application Germany Mar. 16, 1967

Term of patent 14 years

(Cl. D26—14)

FIG. 1

FIG. 2

FIG. 3

FIG. 4

FIG. 5

FIG. 1 is a front elevation view of the television telephone embodying my design;

FIG. 2 is a rear elevation view thereof;

FIG. 3 is a side elevation as viewed from the right of FIG. 1, the undisclosed opposite side is a mirror image thereof;

FIG. 4 is a top plan view thereof; and

FIG. 5 is a cross-sectional view of the bottom thereof taken along line 5—5 in FIG. 1.

The elements shown in broken lines are included for illustrative purposes only.

I claim:

The ornamental design for a television telephone, as shown and described.
